CLAIM

We claim the ornamental design for an electrical ioniser, as shown.

DESCRIPTION

FIG. 1 is a perspective view from underneath and to the right of the electrical ioniser according to the invention;

FIG. 2 is a view from the left of the electrical ioniser according to the invention;

FIG. 3 is a perspective view from above and to the right of the electrical ioniser according to the invention;

FIG. 4 is an enlarged front view of the electrical ionizer according to the invention;

FIG. 5 is an enlarged rear view of the electrical ionizer according to the invention; and,

FIG. 6 is a perspective view from the right and the rear of the electrical ioniser according to the invention.

The broken line showing is included for the purpose of illustrating and forms no part of the claimed design.
